Inventor:

James W. Mann

United States Patent Office.

JAMES H. MANN, OF LEWISTOWN, PENNSYLVANIA.

Design No. 2,948, dated March 10, 1868.

DESIGN FOR AN AXE-LABEL.

The Schedule referred to in these Letters Patent and making part of the same.

TO ALL WHOM IT MAY CONCERN:

Be it known that I, JAMES H. MANN, of Lewistown, in the county of Mifflin, and State of Pennsylvania, have originated a new Design for an Axe-Label, of which the following is a full, clear, and exact description, reference being had to the accompanying drawing, making part of this specification.

This invention is a design for a label to be pasted upon axes at the manufactory where they are made.

It consists of a rectangular field of red, having at its centre a scroll or plate, on which is represented an Indian warrior standing in a field, with an axe lying on the ground near him. Around the scroll or plate are the words, "The Red-Warrior Axe, Manufactured near Lewistown, Pennsylvania, by William Mann."

What I claim as my invention, and desire to secure by Letters Patent, is—

The design for an axe-label, substantially as described and shown.

To the above specification of my invention I have signed my hand, this twenty-second day of January, 1868.

JAMES H. MANN.
